UNITED STATES PATENT OFFICE.

BENJAMIN F. HOOVER, OF SEATTLE, WASHINGTON.

LIQUID-DISPENSING APPARATUS.

1,137,403.

Specification of Letters Patent. Patented Apr. 27, 1915.

Application filed December 8, 1913. Serial No. 805,397.

To all whom it may concern:

Be it known that I, BENJAMIN F. HOOVER, citizen of the United States, residing at Seattle, in the county of King and State of Washington, have invented certain new and useful Improvements in Liquid-Dispensing Apparatus, of which the following is a specification.

The present invention relates broadly to new and useful improvements in liquid dispensing apparatus and aims as its principal object to provide a construction of this character which may be employed as a means for discharging a liquid such as water upon 10 telegraph poles, telephone poles or posts, in case of fire.

The invention aims still further to construct the apparatus in such manner that it may be employed in applying a wood preservative to the poles or posts so that the 20 life thereof will be prolonged.

A still further object of the invention is to employ a pipe system in connection with telephone or telegraph lines, laying a main 25 adjacent the line of the poles and running a branch pipe from the main to each pole, directing the pipe upwardly along the pole and equipping the upper terminal of the branch pipe with a nozzle adapted to 30 discharge the preservative against the top of the pole whereby it will drip down to completely coat the pole throughout its length.

The above and additional objects are accomplished by such means as are illustrated 35 in the accompanying drawings, described in the following specification, and then more particularly pointed out in the claims which are appended hereto and form a part of this application.

40 The figure is a side elevation showing the invention in its application to a telephone pole.

In this drawing, the portion of the apparatus which is below the ground is illustrated 45 in section as is the discharge nozzle which is carried at the upper terminal of the branch pipe, which leads from the main pipe to the individual pole.

Coming now to the description of the 50 drawings, a main indicated at 10 is laid adjacent the telephone or telegraph line. Branch pipes 11 are tapped into this main at intervals and are directed upwardly along the telegraph poles, being bent at their upper 55 terminals as at 12 to provide a portion

which is disposed above the upper terminal of the poles.

A nozzle indicated as an entirety by the numeral 13 is positioned at the terminal of this goose-neck portion 12 and is arranged to 60 discharge water or preservative liquid upon the pole at its upper terminal.

Preferably, the nozzle includes an outer casing 14 and an inner casing 15 which latter member is held in spaced relation to the 65 outer casing by means of attaching brackets 16. The outer casing, at its upper terminal, is substantially conical so that the upper portion of its wall, indicated at 17, diverges 70 downwardly from the longitudinal axis of the nozzle. At an approximate central point of the casing 14, the wall is directed inwardly so that it is downwardly convergent toward the longitudinal axis of the 75 nozzle as indicated at 18.

The inner casing 15 is somewhat similar in shape to the outer casing. The upper portion of its wall indicated at 19 diverges 80 downwardly and approaches the wall 17 of the outer casing, being most nearly adjacent the portion 18 at an approximate central point of the nozzle. The lower portion 20 of the inner casing is also downwardly convergent toward the longitudinal axis of the nozzle, but its divergency is of a less degree 85 than that of the portion 18 of the outer casing. It will thus be seen that the inner casing approaches the outer casing throughout its length until it is only slightly spaced from the outer casing at its lower terminal 90 21. The annular passage 22 which is thus produced between the lower terminals of the inner and outer casings is relatively narrow. It will now be apparent that the liquid in discharging from the nozzle 13, will be sent 95 forth in a substantially conical sheet so that all points of the upper terminal of the pole will be thoroughly coated with the liquid.

It will therefore be seen that in the event 100 any of the poles of the line should get on fire, water may be forced through the main 10 to be discharged through the branch pipes 11, whence, it will be distributed by the nozzles upon the poles or when it is desired 105 to apply the preserving liquid to the poles, such liquid may be readily disposed thereon by forcing it through the main. In this connection, it is to be observed that the nozzle 13 is so constructed as to distribute the preserving liquid over the entire ex- 110

posed surface of the poles. A turn plug 23 is preferably interposed in each of the branch pipes 11 so that the main may be normally cut off from communication with the nozzles 13, this construction having a further advantage in that when it is desired to apply water or a preservative liquid to any certain pole of a line, communication of the main 10 with the other poles of the line 10 may be shut off.

In reduction to practice, it has been found that the form of this invention illustrated in the drawings, and set forth in the above description as the preferred embodiment, is the 15 most efficient and practical, yet realizing that the conditions concurrent with the adoption of this device will necessarily vary, it is desired to emphasize the fact that various minor changes in details of construction, 20 proportion, and arrangement of parts may be resorted to, when required, without sacrificing any of the advantages of this invention, as defined in the appended claims.

Having thus described my invention, what 25 I claim and desire to secure by Letters Patent is:—

1. In an apparatus of the character described, a main pipe, a branch pipe, a valve controlling the flow of liquid from the main 30 pipe to the branch pipe, and a nozzle carried by the upper terminal of the branch pipe, said nozzle including an outer casing, an inner casing, and brackets supporting the inner casing in position in the outer casing, said last mentioned casing having substantially conical upper and lower portions, the 35 base portions of which join at the approximate center of the casing, said inner casing also having substantially conical upper and 40 lower portions, the bases of which join at the approximate center of the inner casing, the lower conical portion of the inner casing

being shaped to approach the lower conical portion of the outer casing toward the extreme lower terminal thereof, whereby a restricted annular passage is formed between the lower edge portions of the inner and outer casings for discharging the liquid issuing from the nozzle in a substantially conical sheet. 45

2. In an apparatus of the character described, a main supply pipe, a branch pipe, a valve controlling issuance of liquid from the main pipe to the branch pipe, and a discharge nozzle carried by the branch pipe, 50 said nozzle including an outer casing consisting of upper and lower substantially conical portions, the upper conical portion having a relatively small opening communicating with the branch pipe, the lower terminal of the lower conical portion having a relatively large opening, an inner casing supported within the outer casing and spaced therefrom, said inner casing including a substantially conical upper portion, the apex of 55 which is arranged in longitudinal alinement with the opening of the branch pipe, and a substantially conical lower portion, the lower edge of the inner casing being spaced from the adjacent portion of the outer casing a less distance than is the upper conical portion of the inner casing spaced from the adjacent portion of the outer casing, whereby a relatively narrow annular opening is formed between the lower edges 60 of the inner and outer casings for discharging the liquid issuing from the nozzle in a substantially conical sheet. 65

In testimony whereof I affix my signature in presence of two witnesses.

BENJAMIN F. HOOVER. [L. S.]
